UNITED STATES PATENT OFFICE.

SYLVESTER L. GOOKIN, OF BOSTON, MASSACHUSETTS, ASSIGNOR TO UNITED SHOE MACHINERY COMPANY, OF PATERSON, NEW JERSEY, A CORPORATION OF NEW JERSEY.

EYELETING-MACHINE AND THE LIKE.

1,184,092.

Specification of Letters Patent.

Patented May 23, 1916.

Application filed July 23, 1914. Serial No. 852,708.

To all whom it may concern:

Be it known that I, SYLVESTER L. GOOKIN, a citizen of the United States, residing at Boston, in the county of Suffolk and State 5 of Massachusetts, have invented certain Improvements in Eyeletting-Machines and the like, of which the following description, in connection with the accompanying drawings, is a specification, like reference characters 10 on the drawings indicating like parts in the several figures.

This invention relates to improvements in machines for setting eyelets or other tubular fasteners and more particularly to 15 setting tools for such machines.

Blind or invisible eyelets are set in one part of a shoe upper in register with a hole punched in the other part for the passage of the lacing. Eyelets set in the lining beneath 20 a hole in the outer part of the upper are designated as invisible eyelets, and eyelets set in the outer part of the upper above a hole in the lining are designated as blind eyelets. The eyelets of both classes may be 25 set by substantially the same tools, the only difference being in the manner of presenting the work to the machine.

There is more or less variation in the thickness of the different layers of sheet 30 material which make up the various shoe uppers to be eyeleted in a shoe factory. The conditions also are frequently varied by the introduction or the omission of one or more layers of textile material for stiffening.

35 An object of the present invention is to provide an upsetting tool which may be used successfully for setting blind or invisible eyelets in shoe parts of varying thickness. This, it is believed, has never before been at- 40 tempted.

In accordance with one feature of the present invention the pilot and upsetting surface of the upsetting tool are made relatively adjustable and the tool is arranged 45 to enter the shoe upper as it rests upon a support. By adjusting the upsetting surface nearer to or farther from the end of the pilot the upsetting surface may be made to pass varying distances into the upper so 50 that when an eyelet is subsequently inserted from the other side of the upper its end will be clenched at the proper place. For example, if invisible eyelets are to be set in a lining of unusual thickness or a lining re- 55 inforced with a thick stiffening strip the

upsetting surface will be adjusted to a point farther above the end of the pilot than would be the case in setting an invisible eyelet in a thin lining.

Another important feature of the invention consists in the provision of an upsetting tool of which the upsetting surface and pilot are relatively adjustable so that in one position of relative adjustment blind or invisible eyelets may be set, and in another 60 position of relative adjustment eyelets may be set in the usual manner, that is, with their flanges on one side of the work and their barrels passing entirely through all portions of the work and being clenched 65 upon the opposite side. In accordance with the present invention this is effected by adjusting the upsetting surface sufficiently 70 above the end of the pilot to insure that the upsetting surface shall not enter the work 75 but permit the eyelet barrel to pass entirely through it before the clenching operation takes place. This feature of the invention is of importance because it enables the operator to use the same machine, fitted with 80 the same tools, for "blind work" or for regular work, and in practice the requirements may change with every case of shoes that comes to the operator. As herein shown, 85 though not necessarily, the pilot is utilized as a punch and such construction constitutes another important feature of the invention. The cutting bed also may, to good advantage, be utilized as the work support in which case the upsetting surface will be 90 forced into the upper to the proper point during the punching operation. This arrangement is advantageous in that it insures great uniformity of operation and consequently work of good quality. 95

The invention is described as an improvement in eyeletting machines and its most useful application is in this field although it is contemplated that the upsetting tool herein disclosed may be utilized for inserting lacing 100 hooks if so desired.

The features above discussed and others will be best understood and appreciated from the following description of a preferred embodiment of the invention selected for purposes of illustration and shown in the accompanying drawings, in which,—

Figure 1 is a view in perspective of the operative parts of an eyeletting machine embodying the invention; Fig. 2 is a view in 110

perspective on an enlarged scale of the upsetting tool; Fig. 3 is a sectional view showing the parts of the machine in the position which they occupy at the conclusion of the 5 punching operation; Fig. 4 is a similar view showing the parts of the machine in the position which they occupy at the conclusion of the setting operation, and Fig. 5 is a similar view showing the upsetting tool adjusted for 10 setting eyelets in the regular manner.

The invention is herein illustrated as embodied in a machine known as the Samson eyeletting machine and which is fully described in a co-pending application of Walter Shaw Serial No. 749,640, filed February 20, 15 1913, although it will be apparent that any well known eyeletting machine would serve as well. As in the machine of the application the machine herein shown has a frame 2 in which is mounted for vertical reciprocation a plunger 6. The lower or eyelet carrying set 8 is adjustably mounted in the plunger 6 and is provided with the usual center 20 spindle 10. Eyelets are supplied to the set 8 during its upward movement by a race-way not shown. A work table 4 is secured to the frame and is perforated to permit the 25 passage of the lower set 8. A presser foot 12 serves to clamp the work in place upon the table 4 during the intermissions between the feeding steps. At the rear of the work 30 table there is mounted a lever 14 which carries the upsetting tool and is given, in addition to its vertical movement, a transverse 35 movement to feed the work. The work table 4 is slotted to receive a hardened cutting block 16 which acts also as a work support during the punching operation.

The upsetting tool, of which the punch 40 forms a part, consists of a cylindrical shank portion 20, a reduced threaded portion 22, a punch 24 of smaller diameter, and a sleeve 26 upon which is formed the upsetting surface 28. The punch 24 is tubular and 45 communicates with a passage extending upwardly through the body portion of the tool so that the punchings may be ejected through its upper end. The sleeve 26 is internally threaded and fitted upon the portion 22 of the tool. It has an enlarged and knurled body portion by which it may be gripped and turned by the operator while at its lower 50 end it is tapered inwardly to form a cylindrical collar 32 of relatively small diameter. The upsetting surface is formed on the lower 55 edge of this collar and practically merges into the outer cylindrical surface of the punch 24 which thus constitutes the pilot of the upsetting die.

The combined upsetting and punching 60 tool is adjustably mounted in the forward end of the lever 14, being backed up by an adjustable bearing piece 40 which is threaded into the lever 14 and provided with a lock 65 nut 42. A set screw 44 is provided for re-

taining the tool in place while its position in the lever is determined by the setting of the bearing piece 40.

It will be apparent that by turning the sleeve 26 upon the threaded portion 22 of the 70 tool the upsetting die surface 28 will be carried nearer to or farther from the end of the punch 24. As this part of the punch is forced completely through the work in the 75 punching operation the depth to which the upsetting surface will be forced into the work may be accurately determined by the setting of the sleeve 26.

In Fig. 3 the machine is illustrated as adjusted for inserting blind or invisible eyelets in the lining 54 and stiffening strip 52 of an upper beneath the hole for the lacing formed in the outer part 50. As shown in this figure the end of the punch is forced through the work into engagement with the 85 surface of the cutting block 16 and the upsetting die surface has been crowded into the hole in the outer part 50 of the upper and carried approximately through this part of the work. In the operation of the machine 90 the tool is then lifted just sufficiently to clear the surface of the cutting block and moved toward the left feeding the work with it until it comes into vertical alinement with the lower set 8. The latter is then elevated 95 and an eyelet forced into the upper until the end of its barrel encounters the upsetting surface by which it is clenched. This condition of affairs is illustrated in Fig. 4.

The position of the upsetting surface 28 100 in the work may be adjusted with extreme accuracy and the clenched end of the barrel accordingly may be brought wherever desired. With the tool as adjusted in Fig. 3 the eyelet barrel passes through two thicknesses, the lining 54 and the stiffening strip 105 52, before its end is clenched, but by slightly lowering the sleeve 26 the upsetting surface may be made to enter the stiffening strip 52 so that the eyelet will be clenched upon 110 the surface of the lining 54 and independently of the stiffening strip 52 if this were to be desired. On the other hand the sleeve 26 may be moved upwardly and the upsetting surface 28 located at a greater distance 115 from the end of the punch 24. Such an adjustment is illustrated in Fig. 5 where the sleeve 26 is shown as elevated sufficiently to permit the eyelet barrel to pass through all parts of the work and to be clenched upon 120 its outer surface. With the tool so adjusted therefore, eyelets may be set in the usual manner.

It will be seen that the different adjustments provided for in the above described 125 tool permit all parts of the machine to be positioned to the best advantage with respect to their cooperating parts. The bodily adjustment of the tool afforded by the bearing piece 20 permits the precise adjustment 130

of the punch with respect to the cutting block 16 which is essential for properly perforating the work. The adjustment of the sleeve 26 upon the tool permits the proper 5 location of the upsetting surface without in any way disturbing the previously adjusted relation of the punch and cutting block.

Having thus described my invention, I claim as new and desire to secure by Letters 10 Patent of the United States:

1. An eyeleting machine having, in combination, an eyelet carrying set, a cutting bed, and a tool comprising a punch and an upsetting die constructed and arranged for 15 relative adjustment.

2. An eyeleting machine having, in combination, a cutting bed, a punch arranged to coöperate therewith, and an upsetting die adjustably mounted on the punch.

20 3. An eyeleting machine having, in combination, a cutting bed, a punch arranged to coöperate therewith, and an upsetting die mounted on the punch for adjusting movement toward or from the plane of the cutting edge of the punch.

4. An eyeleting machine, having in combination, an eyelet carrying set, a cutting bed and a tool comprising a punch and an upsetting die constructed and arranged to 30 permit adjustment of the upsetting die with respect to the eyelet carrying set without affecting the relation of the punch and cutting bed.

5. An eyeleting machine having, in combination, an eyelet carrying set, a cutting bed, a tool carrying member, and a tool comprising a punch for coöperating with the cutting bed and an upsetting die for coöperating with the eyelet carrying set, the tool 40 being adjustably mounted in the carrying member and the parts of said tool being relatively adjustable whereby the proper adjustment of each pair of coöperating elements may be secured independently.

45 6. An eyeleting machine having, in combination, an eyelet carrying set, and a coöperating setting tool having an upsetting surface and pilot which are relatively adjustable.

50 7. An eyeleting machine having, in combination, an eyelet carrying set, and a coöperating setting tool having an upsetting surface and a pilot which may be set in one position of relative adjustment for setting 55 blind eyelets and in another position of relative adjustment for setting eyelets entirely through all parts of the work.

8. An eyeleting machine having, in combination, a cutting bed, and a tool comprising a punch and an upsetting die, said die 60 being adjustable on the punch whereby the distance between it and the cutting bed at the conclusion of the punching operation may be adjusted.

9. An eyeleting machine having, in combination, a cutting bed for supporting work consisting of two or more layers of sheet material, and a coöperating tool comprising a punch and an upsetting die constructed and arranged for adjustment with respect 70 to the punch, so that said upsetting die may pass into the upper layer of the work or not as desired when the punch passes entirely through the work.

10. An eyeleting machine having, in combination, an eyelet carrying set, and a coöperating tool comprising a tubular punch and a sleeve adjustably mounted on the punch and having an upsetting surface formed on 75 its lower edge.

11. A tool for an eyeleting machine, comprising a punch and an adjustable annular upsetting member surrounding the punch and having a relatively small outer diameter whereby it may be crowded into the hole 80 formed by the punch.

12. An eyeleting machine, having, in combination, an eyelet carrying set, a work support, a tool carrying member, and a tool adjustably mounted in said member and 90 comprising a pilot and a relatively adjustable upsetting die, the tool being movable toward the supported work to enter the pilot therein and to carry the upsetting die to a predetermined but controllable distance 95 from the plane of the support.

13. A tool for an eyeleting machine, having, in combination, a reduced end constituting a cylindrical pilot, a threaded portion 100 above the pilot, and a sleeve adjustably mounted upon said threaded portion and having an outwardly and upwardly curved upsetting surface formed upon its lower end, which surface substantially merges into the peripheral surface of the pilot in all adjusted 105 positions of the sleeve.

In testimony whereof I have signed my name to this specification in the presence of two subscribing witnesses.
